UNITED STATES PATENT OFFICE.

WILLIAM PAPPAS, OF BERKELEY, CALIFORNIA.

FOLDING BED.

1,246,781.

Specification of Letters Patent. Patented Nov. 13, 1917.

Application filed February 1, 1915. Serial No. 5,407.

To all whom it may concern:

Be it known that I, WILLIAM PAPPAS, a subject of the King of Greece, residing at 1820 Fifth street, Berkeley, in the county of 5 Alameda and State of California, have invented certain new and useful Improvements in Folding Beds, of which the following is a specification.

This invention relates to improvements in 10 wall beds and more particularly to the type adapted to be moved into and out of a wall recess through an opening smaller than the width of the bed. The principal object of my invention is to provide an improved 15 mechanism by which the bed is constrained to move in a certain path. Also to provide mechanism by which, when the bed is within the closet, it may be pushed farther back from the door than the first-mentioned 20 mechanism would place it.

Another object of my invention is to provide an improved supporting means for the bed frame whereby the same may be easily folded and unfolded.

25 With these and other objects in view my invention consists in the certain novel features and construction as set forth in the following specification and more particularly pointed out in the appended claim, 30 from which it will be apparent that I do not restrict myself to the showing made on the drawing, but may adopt any variation within the scope of the claim.

Referring to the drawings,

35 Figure 1 is a view in plan of a recess into which my bed is adapted to be moved showing the lower portion of the bed positioned outside of this recess, also showing the same in dotted outlines positioned within the recess.

40 Fig. 2 is a view in side elevation of the bed outside of the recess walls, also showing in dotted outlines the bed in its lowered position.

45 Fig. 3 is a view in plan of the undertruck used with my bed.

Fig. 4 is an enlarged view in plan of a 50 segmental track used to guide the bed as it is moved within the recess and withdrawn therefrom.

Fig. 5 is a view in section on 5—5, Fig. 4.

Fig. 6 is a view in section on 6—6, Fig. 4.

Fig. 7 is an enlarged view in side elevation showing the manner in which the legs 55 at the foot end of the bed are attached thereto.

Fig. 8 is a view in section on 8—8, Fig. 7.

Fig. 9 is an enlarged sectional view showing the pivoted connection between the stationary base and the movable side members 60 of the bed.

Fig. 10 is a view in section on 10—10, Fig. 9.

Fig. 11 is a view in side elevation of the mechanism shown in Fig. 9.

65 Referring to corresponding parts by the same numerals of reference, 1 denotes the closet or recess having a door 2, of the usual width and construction, and 3 denotes the movable folding bed, having a bottom frame 70 or truck, denoted in general by 4. This truck comprises the transverse or side members 5, a central member 6, these members being connected by certain cross members 7 and 8. Pivots attached to the members 5 75 are certain links 9 at each end of the frame, these links being provided adjacent their free ends with slots 10 through which extend bolts 11. The member 6 is also provided with slots 12 through which the said 80 bolts 11 extend thereby maintaining these bolts in the center of the truck. The latter is provided on the under side with casters 13 by which the weight of the truck and superimposed mechanism is supported.

85 Slidably mounted on this truck is another frame work having the transverse members 14 and the central member 15, which rest respectively on the members 5 and 6. The member 15 is connected to the bolts 11 and 90 there is also provided a central bolt 16, which extends through a slot 17 in member 6, thus holding the upper frame work in sliding engagement with the truck 4.

95 On each end of the sliding frame work are mounted the U-shaped members 20 having the upstanding arms 21 and 22, to the former of which is attached an ornamental head 23, and to the latter are pivotally mounted the side members 24 of the bed 100 frame. The manner of forming this latter mounting is shown in Figs. 9, 10 and 11 wherein the upright member 22 is formed with a T-shaped head 25 to which is attached a cap 26 and formed between this head 105 and cap is a bearing 27 adapted to receive the shaft 28. The latter is shouldered as at 29 to prevent lateral movement in the bearing 27, is riveted to the longitudinal member 24 as shown at 30, and extends into an opening 31 in the side thereof, thus preventing any tendency to rotate about the rivet 30.

On the inside of the T head 25, a circular disk like member 32 is rigidly attached to the projecting end of shaft 28, and on this member is formed a lug 33 wherein is 5 fastened the tubular head piece 34. The latter extends from one side of the bed to the other, being connected at the opposite side into a similar member 32, and is adapted to hold the mattress and bed clothes in position when the bed is placed in its folded position.

Diametrically opposite the lug 33 is formed an abutment 35 below which is pivotally mounted the socket 36, this socket 15 being provided with a flat portion 37, which is adapted to contact with the abutment 35 when the bed is lowered. Attached in socket 36 is a leg 38, and it will be apparent that the method of mounting this leg is such 20 that when the bed is lowered the bottom of this leg will rest on the floor and throw the weight of the bed on the leg, thus relieving the casters of the truck 4 from the added weight of the occupants in the bed.

25 The foot end of the bed is also provided with legs, which are attached as shown in Figs. 7 and 8, wherein a bracket 40 is riveted to the lower edge of the longitudinal side members 24 and to this bracket is permanently attached the upright ornamental 30 foot piece 41. The legs 42 are provided with a lateral extending lug 43, which is then bent upwardly parallel to the leg itself, is bifurcated, and pivotally attached to the 35 bracket 40.

In order to guide the bed in its movement into the closet, I provide a segmental shaped track 45, which is attached to the floor by means of screws passing through the lugs 46 on the ends thereof. This track is arc shaped and slidably mounted therein is a member 47 curved to conform with an arc shaped track and having at one end the reduced portion 48 on which is slidably mounted the bracket 49, this bracket being in turn attached to the transverse members 5 at the back of 4. By having these portions 48 slidably on bracket 49, the bed or truck on which the bed is carried is permitted a large angle 45 of movement without an undue increase in 50 the amount of space required by the members guiding the truck.

To assist in the folding of the bed, I provide substantially S-shaped springs 51 on each side of the bed. These springs have one end as at 52 rigidly attached to the upper ends of the members 21, the other end pivotally attached to the end of the longitudinal side members 24. The springs are

placed in position under tension so that the 60 tendency of the free end attached to 24 is to expand outwardly thus exerting a pressure to raise the bed upwardly. This pressure is greater when the bed is in its lower position, thus requiring a substantial uniform form effort to raise the bed.

While having thus described the various features of my invention, the operation is as follows:—Assuming that the bed is positioned outside of the recess as shown in Fig. 70 1, when a side pressure is exerted on the bed, the first action is to cause the bracket 49 to slide on the circular portion 48 until this bracket comes in contact with the shoulder of 47. The latter is then moved inwardly around the track 45, carrying the truck 4 and the superimposed bed into the recess in a predetermined path. Once within the recess it is desirable to have additional room at each end of the closest adjacent the 80 door, which is obtained by sliding the upper frame work which carries the bed on the lower truck 4. In this manner the bed is enabled to be pushed through a door of minimum width and at the same time a 85 maximum amount of room is obtained in the closet for the disposal of garments.

It will thus be apparent that I have provided a novel construction, and while I have shown the preferred embodiment of my invention it will be understood that changes in detail and design may be resorted to without departing from the scope of the claim.

What I claim as new and wish to cover by Letters Patent is:—

The combination with a truck of a framework slidably mounted thereon, and a bed frame pivotally mounted on said framework, said truck having parallel side members and a central member intermediate said side 100 members, said central member having longitudinal slots therein, said framework having a central member immediately over said central member of said truck, bolts passing through the central member of said framework and said slots in the central member of said truck, and pivoted arms carried by the side members of said truck, and extending inwardly therefrom, said pivoted members having slots at their inner ends through 105 which said bolts also pass.

In testimony whereof I affix my signature in presence of two witnesses.

WILLIAM PAPPAS.
